UNITED STATES PATENT OFFICE.

JOHN WILSON BROWN, JR., OF PHILADELPHIA, PENNSYLVANIA.

DESIGN FOR A CASING FOR FRUIT-PRESSES.

SPECIFICATION forming part of Design No. 24,592, dated August 20, 1895.

Application filed July 9, 1894. Serial No. 517,014. Term of patent 14 years.

To all whom it may concern:

Be it known that I, JOHN WILSON BROWN, Jr., a citizen of the United States, residing in Philadelphia, Pennsylvania, have invented a certain Design for the Casing of a Fruit-Press, of which the following is a specification.

My design for the casing of a fruit-press is fully illustrated in the accompanying drawing, in which the figure is a side view illustrating my design.

A is a tapered barrel, and depending from the large end of the barrel is a leg C, having feet c, by which it is secured to a table, and mounted above the large end of the barrel is a hopper B. Extending from the narrow end of the barrel is an overhanging bracket D,

curved as shown and terminating in a portion d, which is perforated in line with the center of the barrel. At the junction of the barrel and the supporting-leg is an inclined trough a. 20

I claim—

The design for the casing of a fruit press, as herein described and shown in the accompanying drawing.

In testimony whereof I have signed my name to this specification in the presence of two subscribing witnesses.

JOHN WILSON BROWN, JR.
